(57) **CLAIM**

I claim; the ornamental design for a small tools pouch organizer, as shown and described.

DESCRIPTION

FIG. 1 is a perspective view of a small tools pouch organizer showing my new design;

FIG. 2 is a front elevation view thereof;

FIG. 3 is a rear elevation view thereof;

FIG. 4 is a top view with the sections closed thereof;

FIG. 5 is a top view with the sections open thereof; and,

FIG. 6 is a left end elevation view thereof, the right end being a mirror image.

The bottom of the small tools pouch organizer is flat and unornamented.

The small tools pouch organizer is shown with broken lines for illustrative purpose only and forms no part of the claimed design.

The small tools pouch organizer can be worn in different options as shown in FIG. 3, with the attached tie strap, or on a separate belt, or on a regular belt worn with the normal clothing.

The rectangle area in FIG. 5 with the fabric symbol represents hook and loop tape for closure.

The small tools pouch organizer is made from cloth.
